US0D1054975S

(12) **United States Design Patent** (10) **Patent No.:** **US D1,054,975 S**
(45) **Date of Patent:** **** Dec. 24, 2024**

(54) **MOBILE POWER BANK**

(71) Applicant: **Shenzhen Utopia-Originality Technology Co., Ltd**, Shenzhen (CN)

(72) Inventor: **Hongyuan Lu**, Shenzhen (CN)

(73) Assignee: **Shenzhen Utopia-Originality Technology Co., Ltd**, Shenzhen (CN)

(**) Term: **15 Years**

(21) Appl. No.: **29/848,025**

(22) Filed: **Jul. 29, 2022**

(51) LOC (14) Cl. **13-02**

(52) U.S. Cl.

USPC **D13/108**

(58) **Field of Classification Search**

USPC D13/103, 104, 105, 106, 107, 108, 110, D13/112, 113, 114, 116, 118, 119, 122, D13/184, 199; D14/251, 253, 432, 434, D14/447

(57) **CLAIM**

The ornamental design for a mobile power bank, as shown and described.

DESCRIPTION

FIG. 1 is a perspective view of a mobile power bank, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
